(57) **CLAIM**

The ornamental design for a plastic media filled blast/ballistic mobility wall, as shown and described.

DESCRIPTION

FIG. 1 is a front right perspective view of the plastic media filled blast/ballistic mobility wall in an assembled view showing my new design;

FIG. 2 is a left rear perspective view thereof;

FIG. 3 is a bottom perspective view thereof;

FIG. 4 is an enlarged front perspective view for clarity of illustration of a first component thereof;

FIG. 5 is a rear perspective view thereof;

FIG. 6 is a front elevation view thereof;

FIG. 7 is a rear elevation view thereof;

FIG. 8 is a left elevation view thereof;

FIG. 9 is a right elevation view thereof;

FIG. 10 is a top plan view thereof;

FIG. 11 is a bottom plan view thereof;

FIG. 12 is an enlarged front perspective view for clarity of illustration of a second component thereof;

FIG. 13 is a rear perspective view thereof;

FIG. 14 is a front elevation view thereof;

FIG. 15 is a rear elevation view thereof;

FIG. 16 is a left elevation view thereof;

FIG. 17 is a right elevation view thereof;

FIG. 18 is a top plan view thereof;

FIG. 19 is a bottom plan view thereof;

FIG. 20 is an enlarged front perspective view for clarity of illustration of a third component thereof;

FIG. 21 is a rear perspective view thereof;

FIG. 22 is a front elevation view thereof;

FIG. 23 is a rear elevation view thereof;

FIG. 24 is a left elevation view thereof;

FIG. 25 is a right elevation view thereof;

FIG. 26 is a top plan view thereof;

FIG. 27 is a bottom plan view thereof;

FIG. 28 is an enlarged front perspective view for clarity of illustration of a fourth component thereof;

FIG. 29 is a rear perspective view thereof;

FIG. 30 is a front elevation view thereof;

FIG. 31 is a rear elevation view thereof;

FIG. 32 is a left elevation view thereof;

FIG. 33 is a right elevation view thereof;

FIG. 34 is a top plan view thereof; and,

FIG. 35 is a bottom plan view thereof.
